UNITED STATES PATENT OFFICE.

JESSE L. VAN PEEL, OF PULLMAN, WASHINGTON.

VACUUM FEED SYSTEM.

Application filed August 31, 1926. Serial No. 132,841.

My present invention relates to an improved vacuum feed system of the type employing a vacuum supply tank or reservoir and carbureter, for internal combustion engines. The primary object of the invention is the provision of a simple and compact arrangement of the fuel feeding system by means of which the supply of liquid fuel to the vacuum supply tank may automatically 5 be controlled from the engine cylinders and by the co-operation of atmospheric pressure, and the outlet and feed of liquid fuel from the carbureter to the engine cylinders is also controlled by suction from the engine cylinders. Means are also provided whereby an auxiliary supply of fuel may be drawn from the carbureter and introduced into the cylinders while the normal supply of fuel is cut off and the engine is idling. 10 The invention consists in certain novel combinations and arrangements of parts for accomplishing the above and other objects as will hereinafter be more fully pointed out and claimed. 15 In the accompanying claims I have illustrated one complete example of the physical embodiment of my invention wherein the parts are combined and arranged according to the best mode I have thus far devised for the practical application of the principles of my invention. 20

Figure 1 is a vertical sectional view of the device showing the communicating vacuum tank and carbureter and operating parts, 25 and Figure 2 is a detail sectional view at line 2-2 of Figure 1.

In carrying out my invention the vacuum tank or float chamber 1 and the carbureter or gasoline chamber 2 are fashioned in a single casting having a vertical partition 3 separating the chambers, and a flap valve 4 controls communication between the chambers through the port 5 located near the bottom of the partition. By this compact and 40 close arrangement of parts the level of gasoline in the float chamber or vacuum tank and in the carbureter or feed chamber is maintained at all times on an equality through the action of the valve 4.

The open top of the vacuum tank is closed 45 by means of a top plate 6 secured as by screws to the walls of the tank, and the carbureter, at its top, is closed by means of the flat plate 7 of the angular air tube 8, screws 50 also being employed to secure the plate 7 to the walls of the carbureter chamber.

The supply of gasoline to the float chamber of the vacuum tank is drawn from the usual gasoline supply tank through the nipple 9 and inlet chamber 10, in which chamber is located a cylindrical screen 11 surrounding the ported valve-plug 12 in which is fashioned the seat for the float-controlled needle valve 13.

Directly above the gasoline inlet to the 60 vacuum tank is provided a nipple 14 supported in the top plate 6, and an arched vent pipe 15, open to the atmosphere exterior of the vacuum tank, is connected to the nipple, which latter is fashioned at its lower end, 65 within the vacuum tank with a seat for the vent valve 16 formed at the upper end of the stem of the gasoline valve 13. The seats for the gasoline and vent valves are thus aligned and spaced apart in such manner that the 70 valves on the opposite ends of the stem are always in different positions with relation to their seats. When the gasoline valve is closed as in Figure 1 the vent valve is open 75 to the atmosphere, and vice versa. 80

In the top plate 6 of the vacuum tank a nipple 17 is secured, and connected by the suction pipe 18 to the intake manifold of the engine, and at its lower end, within the vacuum tank, this nipple is fashioned with 85 a valve seat for co-operation with the suction needle valve 19 located within the vacuum tank.

The three valves 13, 16, and 19, are controlled by the action of the float 20 in the 90 vacuum tank 1, which float is provided with a slotted lever arm 21, pivoted at 22, in a bracket depending from the inner or underside of the plate 6, and the lever arm is provided with an end fork 23 loosely engaging the double-flanged collar 24 on the stem of the gasoline and vent valves. The lever arm is connected with the suction valve by means of a spring plate 25 attached at the upper side of the arm, and the free end of 95 this spring plate is forked as at 26 to engage under the collar 27 fixed on the suction-valve stem. The lower end of this stem projects downwardly through the slotted lever arm, and a transversely disposed pin 28 is 100 fixed in the stem below the arm to co-act with the spring plate in the control of the suction valve 19.

When the vacuum tank is filled to the desired level, as in Figure 1, the gasoline valve 110 13 and the suction valve 19 are closed, while the vent valve 16 is open to the atmosphere.

When the supply of gasoline in the vacuum tank is diminished and the level of the liquid falls, the float descends and causes the vent valve to close and the gasoline valve 5 to open to permit flow of gasoline from the gasoline supply tank to the vacuum tank. The suction valve 19 is also opened by the descent of the float through the co-action of the arm 21 and pin 28. The spring 25 however, is designed to sustain the suction valve in closed position, and to retard its opening movement, during the initial falling movement of the float, thereby permitting the level of gasoline in the vacuum tank to fall 10 to a limited distance before the suction becomes operative to refill the vacuum tank with gasoline. The spring 25 resiliently supports the valve in closed position until the valve is positively opened by the co-action of 15 the slotted lever arm and the pin 28 of the valve stem. In this manner the gasoline in the vacuum tank is replenished at less frequent intervals than would be the case were the suction valve immediately opened upon 20 initial movement of the float, and a large supply, rather than a small supply, of gasoline is fed to the vacuum tank.

The fuel supply is drawn from the carbureter chamber through the Venturi nozzle 29 of the valve tube 30, the latter being secured in the top plate 7 of the carbureter and depending into the gasoline supply, and the former projecting upwardly into the angular air tube 8. A manually adjusted 30 needle valve 31 is located within and co-acts with a valve seat in the upper end of the valve tube for controlling the feed of fuel through the Venturi nozzle and the air and gas are mingled as they pass through 35 the screen 34 and past the throttle valve 35 to the intake manifold. The fuel valve 31 is supported at 32 in the bottom of the carbureter and may readily be adjusted from the exterior of the carbureter.

40 The usual choke valve 33 is located in the angular air tube for controlling the admission of air to the fuel for mixture therewith, and like the throttle valve, is controlled from the dash board of an automobile or similar vehicle employing the

motor that is fed with fuel from the vacuum feed system.

An idling valve 36 is used to control passage of fuel through the port 37 located in a wall of the angular tube 8 and opening to 55 the interior of the tube above the closed or partially closed throttle valve. A by-pass or passage 38 extends downwardly through the wall from the port and at the lower end of the passage a vertically arranged pipe 39 is 60 secured. The lower end of the pipe is submerged below the level of the gasoline in the carbureter, and the gasoline for "idling" is thereby provided to furnish vapor, which may be diluted with air passing the partially closed throttle, while the main supply of fuel is cut off by the throttle valve. The valve 36 may be adjusted for controlling the passage of vapor through the port 37 for idling, and this auxiliary supply is drawn 65 to the cylinders by suction in usual manner.

Having thus fully described my invention, what I claim as new and desire to secure by Letters Patent is—

1. The combination with a vacuum tank 75 having alined, spaced, ports and valve seats therefor and a suction valve seat and port, of a stem having heads thereon forming a gasoline valve and a vent valve for co-action with the alined seats, a valve for the 80 suction valve-seat and a stem thereon, a float having a lever arm pivoted in the tank and co-acting with said headed-stem, a pin in the suction valve-stem for co-action with the lever arm, and a spring plate on said 85 arm for coaction with the last mentioned stem.

2. The combination with a carbureter having a feed chamber and an air tube having an integral plate closing said chamber, 90 of a valve tube in said plate opening into the air tube and feed chamber and a fuel valve in said tube, the wall of the air tube having a ported by-pass and an idling valve controlling the ported by-pass, and an idling pipe secured in the plate and communicating with said by-pass and the interior of the feed chamber.

In testimony whereof I affix my signature.
JESSE L. VAN PELT.
